ARTICULATED CLOSURE LID STRUCTURE
FOR RAILWAY JOURNAL BOXESTheodore R. Weber, Latrobe, Pa., assignor to
American Locomotive Company, New York,
N. Y., a corporation of New York

Application May 13, 1947, Serial No. 747,718

5 Claims. (Cl. 308—52)

1

This invention relates to articulated closure lid structures for railway journal boxes, and more particularly to an improved hinge pintle retention means therefor.

More specifically, the invention has reference to a lid-supporting hood and a hinge pintle therefor, forming parts of structures as aforesaid, the object of the invention being to provide means formed integrally with the hood and the pintle which co-act not only to prevent lateral displacement of the pintle but also to prevent rotation thereof.

The present invention has particular application to conventional closure lid structures wherein the lid-supporting hood is constituted by a sheet metal stamping. Thus, it follows that the pintle-receiving apertures formed in the side walls of the conventional hood, present very narrow bearing surfaces to the hinge pintle which wear rapidly in use, when the pintle is not restrained against relative rotation, and necessitates the frequent replacement of such hoods and pintles.

By means of the present invention, relative rotation of the hinge pintle in the apertures provided therefor in the lid-supporting hood is obviated simultaneously with the retention of the pintle against lateral displacement. Consequently, when the lid structure is moved from closed to full open position relative to the journal box, the hinge pintle will move with the hood and, when subjected to vibration and shock, will not rattle, oscillate or rotate relative to the hood. Thus, the pintle-receiving apertures provided in the hood are not subject to wear, and replacement of the hood and pintle is obviated.

Referring to the drawings forming a part of this application, wherein only enough of the structure of the journal box and lid therefor are shown to illustrate the present invention:

Fig. 1 is a fragmentary front view, in elevation, showing only a portion of the hood and journal box cam lug with a hinge pintle in assembled relation therewith, the pintle retention means being shown preparatory to being bent into co-acting relation with the head of the pintle;

Fig. 2 is a side view in elevation showing only the hood in closed position with the hinge pintle retention means bent into final co-acting relation with the head end of the pintle;

Fig. 3 is a fragmentary sectional view taken substantially on the line III—III of Fig. 2;

Fig. 4 is a fragmentary view, similar to Fig. 2, showing a modified form of pintle head;

2

Fig. 5 is a fragmentary sectional view showing only the unheaded end of the pintle associated with the hood;

Fig. 6 is a fragmentary perspective view illustrating another modification of the invention; and

Fig. 7 is a view, similar to Fig. 3, of the modification of Fig. 6.

Referring to the drawings, a lid-supporting hood 10 constituted by a stamped sheet metal member, comprises side walls 11 provided, adjacent their upper ends, with rearwardly extending ears 12 having aligned apertures 13—14 for the reception of a hinge pintle 15 in conventional manner. The hinge pintle connects the hood to the cam lug 16 of a journal box. The remainder of the journal box, the box lid, torsion spring and hood-lid connecting means have been omitted from the drawings.

In accordance with the invention, the ear 12 of the right side wall 11 is provided with an upwardly extending continuation or extension thereof, shown in dot-dash lines in Figs. 1 and 2, adjacent the pintle-receiving aperture 13 thereinto, to form an integral tang or tongue 17 adapted to be initially bent 90° as shown in Fig. 1 and thereafter, after the pintle 15 has been disposed in the apertures 13—14 and cam lug 16, to be bent another 90° upon itself in depending spaced parallel relation with the adjacent side wall 11, as shown in Figs. 2—3. The tongue 17 is formed from waste metal, that is, from metal which would otherwise have been sheared off in stamping the right ear 12. It can be bent from the manufacturing position shown in Fig. 1 to the operative position shown in Figs. 2—3 by means of an ordinary mechanics' hammer. The ear 12 at the left side of the hood is provided with a pressed eye 18 extending the bearing surface of aperture 14 to balance the bearing surface of the aperture 13 which is augmented by the additional support afforded by the bent tongue 17.

Further, in accordance with the invention, the hinge pintle 15 consists of a cylindrical body 19 having, at one end thereof, a flat rectangular head 20, which, when disposed in assembled relation in abutment with the adjacent side wall 11, is disposed directly under the tongue 17 in such close relation to the root of the tongue that the pintle head 20 will serve substantially as an anvil upon which the tongue 17 is bent downwardly, as aforesaid, in overlapping relation with the head 20. This arrangement assures the formation of a bend 21 at the root of the tongue 17 having a substantially uniform radius where-

by fracture of the metal at the bend 21 will not occur. The tongue 17 has a base 22 which is considerably longer than its outer edge 23, therefore assuring that the tongue 17 cannot be battered from the hood. The cold bending and hammering of the tongue strengthens it, and the bent tongue strengthens the right ear 12.

As clearly shown in Fig. 2, after the tongue 17 has been brought into co-operative engagement with the outer face of the pintle head 20, the pintle will not only be retained against lateral displacement and hammering, but will also be restrained against rotation relative to the hood 10 by virtue of the abutment which the bend 21 of the tongue 17 forms across the path of the head 20 in contiguous relation thereto whereby the corner portions 24 of the head 20, for example, are adapted to be engaged by the abutment and relative rotation of the pintle 15 prevented. The pintle 15 can be formed of low cost cylindrical bar stock. It fits with working clearance only in the apertures 13 and 14, providing a long-lived hinge connection. The pintle is adapted to rotate with the lid structure relative to the box lug 16. Therefore wear can occur only at the contacting portions of the cam lug and pintle body 19 and this is prevented in a conventional manner forming no part of the present invention.

Referring to the modification shown in Fig. 4, the arrangement here is identical with that shown in the preceding figures with the exception that the head 20' of the pintle 15' is of flat cam-shaped configuration whereby the peak 25 of the cam head 20' will engage the underside of the bent portion 21' of the tongue 17' and prevent rotation thereof relative to the hood 10'.

It has been found that when the hinge pintle 15' is not restrained against relative rotation and is subjected to vibration, the direction of relative rotation is always clockwise or in the direction of the arrow indicated in Fig. 4. Similarly, upon movement of the lid structure from closed to full open position, the hinge pintle 15' may also rotate in a clockwise direction in response to such angular movement of the hood 10', or, if the pintle 15' remains stationary, it will be in its proper position upon closure of the lid structure.

In view of this condition, a pintle flat faced head need not necessarily be rectangular, as in Fig. 2, but may be of any other configuration provided that a portion thereof extends radially thereof sufficiently to engage the abutment of the underside of the bent portion 21' of the tongue 17' whereby relative rotation of the pintle is prevented.

Figs. 6-7 illustrate another embodiment of the invention wherein the base of the tongue 17'' is reinforced to give it longer life. The tongue 17'' is substantially of the same shape as the tongue 17 but at its forward side 26 it merges with an integral extension 27 which is also formed of waste material which would otherwise be sheared from the ear 12''. Thus the tongue 17'' has an outer edge 23'' of the same length as the edge 23 but has a base 22'' about twice as long as the outer edge 23''. Tongue 17'' is, when in the position shown in Fig. 6, flat and parallel to the adjacent edge of the pintle head 20'' but extension 27 is curved upwardly from its juncture with tongue 17'', this curvature adding to its strengthening characteristics.

In Fig. 7 it is clearly shown that the extension 27 extends from the adjacent side wall 11'' a dis-

tance about the same or slightly less than the outer face of the head 20'' of the pintle 15''. Thus the extension 27 is not bent when the tongue 17'' is bent from its position in Fig. 6 to its operative position in Fig. 7. However, any battering at the abutment 21'' is rendered harmless by the long connection between the tongue 17'' and the side wall 11'' effected by the base 22'' which base is in part integral with the tongue 17'' and in part integral with the extension 27. Actual tests made in a vibratory machine have proven that the inclusion of the extension 27 more than doubles the life of the pintle retaining tongue.

The pintle 15' can be employed with the tongue 17'' if desired. The hood 10'' will be shipped as shown in Fig. 6 so that it can be applied to a journal box and all that will be necessary from the mechanic's standpoint is the hammering down of the tongue 17'' which will be effected in the same way as the hammering down of the tongue 17.

Fig. 5 illustrates the construction at the left side of the hood for all embodiments of the invention. Parts of the structures of Fig. 4 and of Figs. 6-7 corresponding to like parts of the structure of Figs. 1-3 are indicated by like references with distinguishing accents added.

While there have been hereinbefore described approved embodiments of this invention, it will be understood that many and various changes and modifications in form, arrangement of parts and details of construction thereof may be made without departing from the spirit of the invention, and that all such changes and modifications as fall within the scope of the appended claims are contemplated as a part of this invention.

The invention claimed and desired to be secured by Letters Patent is:

1. A hinge construction for articulating a railway journal box and hood comprising a pair of cooperating members provided with apertured portions adapted for the reception of a hinge pintle having a flat, non-circular head at one end thereof; and a tongue formed on one of said apertured portions adapted to be bent over the head of said pintle to a position flat against the outer face thereof to retain said pintle against lateral displacement, said tongue, adjacent its root end, providing a transverse abutment adjacent to and in the path of said head whereby the periphery thereof is adapted to engage said abutment preventing relative rotation of said pintle.

2. In a journal box closure lid structure, the combination of a lid-supporting hood having opposite side walls provided with aligned apertures, a hinge pintle having a flat cam-shaped head at one end thereof, disposed in said apertures with said head in abutment with one of said side walls, and a tongue forming a reversely bent continuation of said one side wall disposed in overlapping engagement with the outer face of said head to retain said pintle against lateral displacement, the reverse bend in said tongue providing a transverse abutment adjacent to and in the path of said head whereby a portion of the periphery of said head engages said abutment preventing rotation of said pintle relative to said hood.

3. In a journal box closure lid structure, the combination of a lid-supporting hood having opposite side walls provided with aligned apertures, a hinge pintle having a flat rectangular head at one end thereof, disposed in said apertures

with said head in abutment with one of said side walls, and a tongue forming a reversely bent continuation of said one side wall depending in overlapping engagement with the outer face of said head whereby to retain said pintle against lateral displacement, the bent portion of said tongue providing a transverse abutment adjacent to and in the path of said head whereby portions of said head are adapted to engage said abutment preventing relative rotation of said pintle.

4. In combination, a journal box lid-supporting hood having side walls and aligned apertures in said side walls; and a hinge pin having a cylindrical body extending through said aligned apertures and a head at one end only in engagement with one of said side walls preventing lateral movement of said pin in one direction, said one side wall having a U-shaped portion providing a depending tongue overlapping and engaging the outer face of said head preventing lateral movement of said pin in the opposite direction, said U-shaped portion augmenting the bearing support of the adjacent aperture, said hood having an integral portion extending laterally from the other of said apertures extending the bearing support thereof at the unheaded end of said pin whereby said bearing supports are balanced, said head and U-shaped portion having co-acting faces preventing rotation of said pin in said apertures in at least one direction.

5. In a journal box closure lid structure, the combination of a lid-supporting hood having opposite side walls provided with aligned apertures, a hinge pintle having a head at one end thereof and disposed in the apertures with the head in abutment with one of the side walls, spaced radial extensions on the head, and a tongue forming a reversely bent continuation of the one side wall and disposed in overlapping engagement with the outer face of the head to retain the pintle against lateral displacement, the reverse bend in the tongue providing a transverse abutment adjacent to and in the path of the head whereby the spaced radial extensions of the head engage the abutment preventing rotation of the pintle relative to said hood.
